This is a continuation-in-part application filed as an original application on July 1, 1947, and a continuation-in-part of application Serial No. 63,326, filed January 15, 1946, and now abandoned, and the present application is well entitled to the benefit of the filing date of the original application, which is January 15, 1946, and the filing date of the present application will be January 15, 1947, and the present application is well entitled to the benefit of the filing date of the original application, which is January 15, 1946, and the filing date of the present application will be January 15, 1947.

UNITED STATES PATENT OFFICE

2,518,925

COMBINATION OIL AND GAS BURNER

Philip L. Knight, Toledo, Ohio, assignor to Surface Combustion Corporation, Toledo, Ohio, a corporation of Ohio

Application March 17, 1948, Serial No. 15,326

1 Claim. (Cl. 158—11)

1

This invention relates to oil and gas burners for industrial use and more particularly to means for converting an already installed gas burner of well known type to an oil burner so that oil instead of gas may be burned when gas is not available. One of the problems involved in converting an already installed gas burner to an oil burner is how to make the change with minimum trouble and expense and with minimum change in the parts of the gas burner assembly. The present invention solves these and other problems in a relatively simple and practical way as will hereinafter more fully appear.

For a consideration of what I consider to be novel and my invention attention is directed to the following specification and the claim appended thereto.

In the accompanying drawings forming part of this specification—

Fig. 1 is a longitudinal sectional view of a gas burner with the oil conversion means of the present invention applied thereto.

Fig. 2 is a transverse section on line 2—2 of Fig. 1.

Fig. 3 is an enlarged sectional view of the oil burner element embodied in Fig. 1.

Fig. 4 shows another way of applying the oil conversion means to the gas burner assembly disclosed in Fig. 1.

One well known type of industrial gas burner with which the present invention is concerned comprises a cylindrical combustion tunnel 11 which is ordinarily formed in a ceramic block 12 adapted to form part of a furnace wall 10, the block extending from a metal holder 13 adapted to be secured to the outer steel casing 14 of said furnace wall. The tunnel is so proportioned as to permit a combustible mixture of air and fuel gas entering through port or passage 15 to be burned to substantial completion within the tunnel so that only highly heated products of combustion enter the furnace chamber proper. The passage 15 is conveniently formed in a metal body 16 having a radial flange 17 for securing it to the outer face of the block holder 13. Heat dissipating fins 20 on said body maintain it relatively cool. The combustible mixture is formed in and by a Venturi mixing tube 22 which is screwed into the outer end 24 of a tubular extension 23 of the body 16.

The mouth of the mixing tube 22 is in open communication with an air chamber 25 to which air under appropriate pressure is delivered by a supply pipe 26 having a throttling valve 27. The air in flowing through the tube 22 entrains fuel

gas from a circumferential ring of gas inlet ports 33 in the side of the tube near the downstream side of the throat of said tube. The ports 33 are in open communication with a surrounding gas chamber 30 to which gas at atmospheric pressure is delivered by means comprising a supply pipe 31 (see Fig. 2) which delivers to a valve body 32 shown as integral with the wall 23 of said chamber. The valve body 32 comprises a dividing wall 29 having a gas port therethrough the effective size of which is controlled by a valve 34 embodying a metering orifice 28 of such effective cross sectional area as will permit substantially all of the gas normally required to flow to said chamber 30.

One of the objects of the present invention is to apply an oil conversion means to a gas burner of the type above described so that oil may be burned when gas is not available as due to gas shortage during cold weather.

In the present invention, the oil conversion means comprises an oil and air conducting tube 35 of relatively small diameter and of a length to extend coaxially within the bore of mixing tube 22 from a supporting head or fixture 36 shown as screwed into the far end wall 37 of the air chamber 25. However, as a preliminary to positioning said tube 35 in said bore, the original mixing tube 22 will be replaced by one of correspondingly larger bore so that the gas entraining capacity of the mixing tube may remain the same as before. The tube 35 is long enough to extend some distance into the passage 15 which leads to the combustion tunnel but with its discharge end far enough back from the entrance to the tunnel to remain relatively cool.

Referring now more particularly to Fig. 3, the head 36 from which the tube 35 extends is made hollow to form an air chamber 44. The tube 35 is in open communication with said air chamber by way of an extension or barrel 41 screwed into the head, the tube in turn being screwed into the barrel, so that the latter is in effect an extension of said tube. The barrel terminates in relatively close proximity to the far end wall of the chamber 44 so as to be in position to receive oil spray from a metering nozzle 40 screwed into said end wall. Oil under pressure is delivered to said nozzle by a supply pipe 42 having a shut-off valve 43. Air under relatively high pressure is delivered to the air chamber 44 by a supply pipe 45 having a shut-off valve 46.

At its discharge end the air and oil conducting tube 35 has a restricted outlet 47 shown as formed in a plug 48 which closes the outer end

of said tube. The said outlet is of such restricted size that the oil on passing through the outlet along with the air will become so finely atomized as to appear as a mist, it being understood the air will issue from said outlet with sufficient velocity to carry the atomized oil into the combustion tunnel 11. Although only a single outlet orifice 47 has been shown there may be a plurality of such orifices depending on the quantity of oil to be atomized per unit of time. The relative proportions of air and oil discharged from the tube 35 will ordinarily be such that the air constitutes about ten per cent of what is required for complete combustion. The balance of the air (secondary air) for combustion is delivered under relatively low pressure to the air chamber 25 by the pipe 26 for flow through the tube 22 to the combustion tunnel 11 as will now be readily understood.

An alternate way of applying the oil atomizing means herein disclosed to the gas burner is shown in Fig. 4. Thus as shown in Fig. 4, a hole may be drilled in the side of the body 16 to receive the air and oil conducting tube (indicated at 50 in this view), the discharge end of the tube being angled so as to be coaxial with the passage 15. The air and oil supplying head 52 (corresponding to the head 36 in Fig. 1) is secured to the body 16 in any preferred way as by means of a supporting bracket secured to said body.

From the foregoing description it will now be readily appreciated that the present invention offers a relatively simple and practical way of converting a gas burner to an oil burner without interfering with the normal mode of operation of the gas burner when gas is available for burning.

What I claim as new is:

In a burner, the combination of a combustion tunnel, structure defining an air passage whose discharge end is coincident with the entrance to said tunnel, wall means defining an air cham-

ber having an air outlet coincident with the air inlet end of said passage so that air under pressure in said chamber may flow directly into said passage for flow therethrough, a relatively slender tube extending into said passage from the air inlet end of the latter to a point short of the air outlet end of said passage for conducting air and fuel oil to a point adjacent the entrance to said combustion tunnel, a hollow head at the inlet end of said tube and from which said tube extends, said head having an inlet for air under pressure and having a separate inlet for fuel oil under pressure; said fuel oil inlet comprising a spray nozzle set to discharge into the inlet end of said tube, and said air passage having a relatively restricted portion intermediate its ends and having at said portion an inlet for fuel gas.
